PACKAGE FOR NEEDLES OR THE LIKE

Joseph Schneider, Eynatten, Belgium, assignor to Manufacture Belge d'Aiguilles, Eupen, Belgium, a corporation of Belgium

Filed Mar. 18, 1964, Ser. No. 79,057

Term of patent 14 years

(Cl. D58—2)

FIG. 1

FIG. 3

FIG. 1 is a front elevational view of a package for needles or the like showing my new design;

FIG. 2 is a side elevational view thereof; and

FIG. 3 is a top view thereof.

The rear of the package is substantially plain.

I claim:

The ornamental design for a package for needles or the like, as shown and described.
